SAFETY RAZOR AND BLADE

Zemach Auerbach, New York, N. Y.

Application November 6, 1941, Serial No. 417,978

22 Claims. (Cl. 30—64)

This invention relates to improvements in safety razors and in razor blades.

Briefly, an object of my invention is to provide an inexpensive razor and blade, simple in construction, easy of operation and which will provide the shaver with a better shave.

More particularly, another object of my invention is to position the double-edged blade so that both cutting edges are in identically the same position from the medial line of the blade platform in order to present identical cutting edges with relation to the guard-cap so that the shaver will have a greater degree of safety.

Another object of my invention is to provide a novel combined platform, guard and cap fashioned of one piece of material to receive a new type of blade which automatically positions the cutting edges of the blade in an exact and predetermined position with relation to the guard.

By my construction, the edges of the blade can be readily washed and wiped without removing the blade from the razor, so that the blade is always ready for immediate use.

Another object of my invention is to provide a novel blade having an applied metal ridge to give the blade longitudinal rigidity and to stabilize the blade during any flexing.

My new blades are constructed so that no tolerance is required since the blade is centrally held by a metal ridge within a channel so that no play is permitted such as the centrally slotted blades now in use.

For a fuller understanding of the nature and objects of my invention, reference is had to the following detailed description in connection with the accompanying drawings, in which

Fig. 1 is a perspective view of the razor, showing a blade partially within the razor head.

Fig. 2 is a top view of the razor shown in Fig. 1.

Fig. 3 is a bottom view of the razor shown in Fig. 1.

Fig. 4 is a side view of the razor shown in Fig. 1.

Fig. 5 is a perspective view of a modified razor with a blade partially within the razor head, and the handle partly broken away.

Fig. 6 is a top view of the razor shown in Fig. 5.

Fig. 7 is a bottom view of the razor shown in Fig. 5.

Fig. 8 is a side view of the razor shown in Fig. 5.

Fig. 9 is a perspective view of another modified razor, showing a blade partially within the razor head.

Fig. 10 is a top view of the razor shown in Fig. 9.

Fig. 11 is a bottom view of the razor shown in Fig. 9.

Fig. 12 is a side view of the razor shown in Fig. 9, with the handle partly broken away.

Fig. 13 is a side view of another modified razor, showing the two halves.

Fig. 14 is a bottom view of the razor shown in Fig. 13.

Fig. 15 is a top view of my new blade.

Fig. 16 is a bottom view of the blade shown in Fig. 15.

Fig. 17 is an end view of the blade shown in Fig. 15.

Fig. 18 is a top view of the modified blade.

Fig. 19 is a bottom view of the blade shown in Fig. 18.

Fig. 20 is an end view of the blade shown in Fig. 18.

Fig. 21 is a sectional view of another modified razor showing a wafer blade in unflexed position within the razor head.

Fig. 22 is a sectional view of the razor shown in Fig. 21, the wafer blade being shown in flexed position.

Fig. 23 is a top view of the razor shown in Figs. 21 and 22.

Fig. 24 is a bottom view of the razor shown in Figs. 21 and 22.

Fig. 25 is a side view of the razor shown in Figs. 21 and 22, with the handle broken away.

Fig. 26 is a top view of another modified blade.

Fig. 27 is a bottom view of the blade shown in Fig. 26.

Fig. 28 is an end view of the blade shown in Figs. 26 and 27.

Referring to the drawings, Figs. 1 to 4, inclusive, numeral 50 represents a razor head fashioned from one piece of material and comprising a platform 51, guards 52—52, and a cap 53—53. Along the longitudinal central portion of platform 51, there is a channel 54. Cap 53 is split along the longitudinal central portion creating an opening 55. Guards 52—52 are bent downwardly at 56. Openings 57—57 are created between the guards 52—52 and cap 53—53. Cap portions 53—53 and platform 51 are slit at 58 so as to create spring members 59—59 which are bent downwardly to contact and hold the razor blade 60 under pressure. Notches 145 are formed in cap 53—53 and platform 51. Attached to channel 54 at its central portion, there is a handle 61. The material of platform 51, guard 52 and cap 53 is made of a material having re-

siliency so that the spring members 59—59 and the cap 53—53 retain blade 60 within the razor head 50 under tension. In injecting blade 60 into the razor head 50, the metal ridge 62 slides within the channel 54 so that the blade is rigidly held exactly along the medial line of the razor thus presenting two identical cutting edges spaced equi-distant from guards 52—52 and spring members 59—59.

Referring to Figs. 5 to 8, inclusive, numeral 63 shows a modified razor head for a double-edged blade 64 having two longitudinal ridges 65—65 spaced a short distance from the cutting edges. Razor head 63 is fashioned of one piece of material comprising a platform 66, guards 67—67 and a cap 68—68. Cap 68—68 is split along the longitudinal central portion creating an opening 69. Guards 67—67 are bent downwardly at 70. Openings 71—71 are created between guards 67—67 and cap 68—68. Cap portions 68—68 and platform 66 are slit at 72 so as to create spring members 73—73 which are bent slightly downwardly in order to contact and hold the razor blade 64 under pressure. Notches 146 are formed in platform 66. Channels 76—76 are created in the spring members 73—73 and the platform 66 permit longitudinal ridges 65—65 of blade 64 to ride within the channels so that the blade is held in proper position. Handle 74 is attached to the bottom of platform 66 by plate 75. The material of platform 66, guards 67—67 and cap 68—68 is made of resilient material so that spring members 73—73 and cap 68—68 retain blade 64 within the razor head 63 under tension. In injecting the blade 64 into razor head 63, the metal ridges 65—65 slide within the channels 76—76 and snap into fixed position when blade 64 is entirely within the razor head 63. Since the channels 76—76 are spaced equi-distant from the longitudinal medial line, the blade 64 presents identical cutting edges with relation to the guards 67—67.

Referring to Figs. 9 to 12, inclusive, numeral 77 shows another modification of my razor head fashioned of two pieces of material, one piece comprising the cap 78 and guards 79—79 and the other, the platform 80 so joined together so as to present an inseparable razor head. The cap 78 and platform 80 have longitudinal channels 81 and 82, respectively, along their medial lines. Guards 79—79 are bent downwardly at 83. Openings 84—84 are created between the guards 79—79 and cap 78. The cap 78 is slit at 85 to allow for movement of spring member 86—86. Spring members 86—86 of cap 78 are bent downwardly to contact and hold razor blade 60 and spring members 87—87 of platform 80 are bent upwardly to contact and hold razor blade 60 under pressure, the platform being slit at 88 to allow for movement of spring members 87—87. Attached to channel 82 at its central portion is a handle 89. The material of razor head 77 is made of resilient material so that spring members 86—86 and 87—87 and the cap 78 retain blade 60 within the razor head under tension. In injecting blade 60 into razor head 77, the metal ridge 62 slides within channels 81 and 82 so that the blade is rigidly held exactly along the medial line of the razor thus presenting two identical cutting edges spaced equi-distant from guards 79—79.

Referring to Figs. 13 and 14, inclusive, numeral 90—90 represents another modified razor comprising two identical halves. Each half is fashioned of one piece of material consisting of

a cap 91, guard 92, platform 93, spring members 94 of cap 91, spring members 95 of platform 93 and handle 96. Along the central longitudinal medial line, the material of the cap 91 and platform 93 is bent at 97 and 98 in a one-quarter arc so that when the halves are joined together a channel is created. Cap 91 and platform 93 are slit at 99, to permit greater flexibility in the spring members which are bent downwardly to contact and hold razor blades like 60. Handle 96 has aligned holes 100 and 101 to receive rivets for joining the two halves of the razor together. In injecting blade 60 into the razor, metal ridge 62 slides within the channel created by 97—97 and 98—98 thus holding the blade rigidly exactly along the medial line of the razor.

Referring to Figs. 15 to 17, inclusive, double-edged blade 60 has a metal ridge 62 running around the central longitudinal portion of the blade and fitting within notches 102—102. Spaced equi-distant from the central ridge 62 there are notches 103—103 at the short ends, 104—104 of the blade.

Referring to Figs. 18 to 20, inclusive, double-edged blade 64 has a pair of metal ridges 65 running longitudinal through opposed holes 105—105 and spaced equi-distant from the longitudinal medial line. In the central portion of the ends 106 of blade 64 there are opposed notches 107.

Referring to Figs. 21 to 25, inclusive, numeral 147 is a razor comprising a cap 148 split along the longitudinal medial line as shown at 149, spring members 150—150, slit at 151—151 in said cap, guards 152—152, a stationary platform 153 and spring members 154—154 slit at 155—155 in said platform. Handle 156 is rigidly attached to the center of platform 153. In stationary platform 153, the material is bent to form a chamber 157. Within chamber 157 there is a movable platform 158 to which is revolvably attached a shaft 159 terminating at the opposite end in a threaded member 160 with a finger knob 161. Shaft 159 passes through handle 156 and threaded portion 160 co-operates with the threaded chamber 162 at the base of handle 156.

The blade 163 shown in Figs. 26 to 28, inclusive, has two ridges 164 embracing the blade and held in position by notches 165 in the edges, the central portion has cut-outs 166.

In operation, blade 163 is inserted within the razor so that ridges 164 of the blade pass into channels 167 of the platform 153. Spring members 150—150 and 154—154 hold the blade under tension. Finger knob 161 is then turned so that moveable platform 158 flexes the blade 163, moving ridges 164 of blade 163 into the upper channels 168 of the cap, forcing the blade to take the position shown in Fig. 36 and the razor is now ready for shaving.

My razors may be made of various types of materials such as metal, plastics or like materials.

It is obvious that various changes and modifications may be made in the various details of construction without departing from the general spirit of my invention, as set forth in the pending claims.

I claim:

1. In a razor of the character described, a one piece razor head for a removable blade, comprising a platform, guards on opposite sides of the longitudinal medial line, longitudinal spring members and cap, said guards being spaced from

the longitudinal medial line so that the cutting edges of a double-edged blade do not come in contact with said guards.

2. In a razor of the character described, a one piece razor head, comprising a platform, opposed guards, longitudinal spring members and cap, said cap being split along the longitudinal medial line.

3. In a razor of the character described, a one piece razor head, comprising a platform, opposed guards, longitudinal spring members and cap, said platform having a channel along the longitudinal medial line.

4. In a razor of the character described, a one piece razor head, comprising a platform, opposed guards, longitudinal spring members and cap, a pair of longitudinal opposed channels in said cap and platform spaced equi-distant from said longitudinal medial line.

5. In a razor of the character described, a one piece razor head, comprising a platform, opposed guards, longitudinal spring members and cap, said cap and platform having opposed longitudinal channels along the medial line of said razor head.

6. In a razor of the character described, a one piece razor head for a removable blade, comprising a platform, guards on opposite sides of the longitudinal medial line, longitudinal spring members and cap, said cap and platform having opposed longitudinal channels along the medial line of said razor head, a handle attached to the central portion of the channel of said platform.

7. In a razor of the character described, a one piece razor head for a removable blade, comprising a platform, guards on opposite sides of the longitudinal medial line, cap and longitudinal spring members on the cap and guard.

8. In a razor of the character described, a one piece razor head comprising a cap, guards on opposite sides of the longitudinal medial line, a stationary platform and spring members on said cap and stationary platform.

9. A razor blade comprising a flat member and an attached longitudinal round wire or round wires on said flat member.

10. A razor blade comprising a flat member having an attached ridge along the round wires on each side of medial line of said blade.

11. A razor blade comprising a flat member having one or more attached round wires longitudinally passing through opposed holes in said flat member.

12. A razor blade comprising a flat member, having a round wire or round wires passing

through opposed notches or holes and embracing said flat member.

13. A rigid double-edged razor blade comprising a flat member and an attached longitudinal round wire or round wires on said flat member.

14. A double-edged wafer razor blade comprising a flat member and an attached longitudinal round wire ridge or round wires on said flat member.

15. A razor blade comprising a normally flat member, a pair of opposed holes near the short edges of said blade and a pair of attached longitudinal round wires embracing said blade and spaced equi-distant from the longitudinal medial line of said blade.

16. A safety razor blade having a normally flat resilient body and supplemental round wires secured to the body of the blade on each side of its longitudinal medial line providing razor 20 gaging means for locating the blade in a safety razor.

17. A double-edged safety razor blade having a normally flat resilient body, and reinforcing round wires secured to the body of the blade and 25 supplying positioning means for inserting said blade in a safety razor.

18. A double-edged safety razor blade having a thin sheet steel body and supplemental round wires longitudinally secured to and embracing 30 said blade thereby reinforcing the blade and serving to support said blade in spaced relation to the guards of a safety razor.

19. A safety razor blade having a normally flat resilient body and supplemental round wires 35 extending longitudinally on each side of the medial line of the blade and embracing the blade supplying positioning means for inserting said blade into a razor.

20. A safety razor blade having a resilient 40 body of thin sheet steel and rigid longitudinal round wires attached to the blade and projecting from both faces of the blade and being arranged to take a greater curvature when the blade is subjected to increasing clamped pressure.

21. A double-edged safety razor blade having a longitudinally resilient body and reinforcing round wires running longitudinally on the blade and embracing both longitudinal faces of the blade.

22. A safety razor blade having a body of thin 50 tempered steel and reinforcing round wire or round wires of different metal than the blade, said reinforcing ridge member or members dividing said blade into various sections.

ZEMACH AUERBACH.
